Attorney.

UNITED STATES PATENT OFFICE.

ALBERT HOMBRECHER, OF BARMEN-LANGERFELD, GERMANY.

SPOOL CARRIER FOR PLAITING, KNOTWORK, BOBBIN, AND LACE-MAKING MACHINES.

Application filed December 30, 1926, Serial No. 158,005, and in Germany July 23, 1926.

My invention relates to a spool carrier for use in connection with plaiting machines, knot-work machines, bobbin machines, and lace-making machines, especially one-thread lace-making machines in which cop spools or conical spools provided with teeth at their upper ends are employed as yarn carriers in lieu of spool with rim flanges.

The invention proper resides therein that 10 the thread coming from the cop bobbin or from the conical bobbin is guided by a head piece attached detachably to the spool carrier above the bobbin, the small flap that regulates and guides the thread further being 15 supported in said head piece.

The spring hitherto used is obviated by that new arrangement and combination of parts, and another advantage resides therein that bobbins of considerably larger diameter 20 can be made use of, because the space required hitherto for the spring can now be filled up with yarn. The drawing-off place of the yarn that was located hitherto always outside the circumference of the bobbin is 25 now located above the yarn and within the circumference of the bobbin. The capacity of the bobbins is enlarged whereby the number of stops of the machine as entailed by the running down of the bobbins is corre- 30 spondingly reduced.

Owing to the use of cops and of conical cross bobbins the pulling off of the thread proceeds by far more easily and uniformly than hitherto. The thread leaves the bobbin 35 smoothly which is useful for the ware produced. It is rendered possible to work up yarns of less tearing resistibility, and besides, the number of revolutions of the machine can be considerably increased. With 40 the highspeed plaiting machines and the like as hitherto designed the possible number of revolutions cannot be utilized because of the insufficiency of the cops, as with a higher number of revolutions the threads tear by 45 reason of the unequal pulling off and, besides, the cops have a too small amount of yarn if smaller stitches are made.

The invention is illustrated diagrammatically and by way of example on the accompanying drawing on which Figure 1 is an axial section through a bobbin carrier designed according to this invention and carrying a conical bobbin, Figure 2 is a top view of the same, Figure 3 a view similar to Fig.

1, but showing a modification designed for 55 cop bobbins, and Figure 4 is a top view of this modification.

On the drawing, *a* denotes a tubular carrier for a spool either such as *n*, Fig. 1, intended to receive a conical bobbin, or such 60 as *b*, Fig. 3, intended to receive a cop bobbin. Detachably attached to the tubular carrier *a* is a head piece *c* located above the bobbin and guided vertically upon the upwardly 65 projecting portion or end of the tubular carrier, a lateral projection of the head piece engaging a vertical slot *g* of said portion or end. The extent of the upward movement of the head piece upon the said portion or end of the carrier *a* is limited by 70 a check *o* which also prevents rotatory movement of the head piece. The enlarged lowermost portion of the head piece *c* serves as carrier for the small flap *d* which co-operates with the ratchet teeth *e* provided at 75 the uppermost end of the spool *n* (Fig. 1) or *b* (Fig. 3) the effect of the co-operation consisting in a uniform delivery of the thread from the bobbin. The thread *h* coming from the bobbin passes first through an 80 eye *p* of the head piece, then over a guide groove *i*, thereafter through an eye *k* of the flap *d*, now through the known spring-actuated eye *l* (*l'* denotes the helical spring pertaining thereto) and finally away through 85 the china eye *m* provided on the top of the tubular spool carrier *a*.

I claim:

1. A spool carrier having means for supporting a conically shaped bobbin, a head 90 cooperating with one end of said carrier having means for conducting thread away from said bobbin, said means receiving the thread in the first instance at a point substantially at the top of the bobbin and within 95 the circumference of the bobbin.

2. A cop carrier comprising in combination a support for a cop, a head piece 100 cooperating with one end of said support for receiving and guiding thread from said cop, said head piece receiving the thread in the first instance at a point above and within the normal largest diameter of the cop.

3. In a device of the class described the combination comprising a support adapted 105 to carry a conically shaped bobbin, a thread guiding head having an eye so positioned with respect to said support that when said

bobbin is mounted on said support said eye will lie within the projection of the largest circumference of said bobbin.

4. In a device of the class described, the combination comprising supporting means for a bobbin, a conically shaped bobbin supported by said means, a thread withdrawing means receiving thread from said bobbin near one end thereof and at a point which
- 5 does not fall without the largest normal circumference of the bobbin.
- 10

5. In a device of the class described, the combination of a supporting means for a cop, a thread guiding means near one end of said supporting means and receiving thread in the first instance at a point between the largest and smallest diameter of the cop used on said supporting means. 15

In witness whereof I have hereunto set my hand.

ALBERT HOMBRECHER.
